UNITED STATES PATENT OFFICE

128,266

DESIGN FOR A GOLF CLUB HANDLE

Kenneth Smith, Lenexa, Kans.

Application April 26, 1941, Serial No. 100,629

Term of patent 14 years

To all whom it may concern:

Be it known that I, Kenneth Smith, a citizen of the United States, residing at Lenexa, in the county of Johnson and State of Kansas, have invented a new, original, and ornamental Design for a Golf Club Handle, of which the following is a specification, reference being had to the accompanying drawing, forming a part thereof.

Fig. 1 is a side elevational view of the golf club handle, showing my design.

Fig. 2 is an edge elevational view thereof.
Fig. 3 is a top plan view thereof; and
Fig. 4 is a cross sectional view taken on line IV-IV of Fig. 2, thereof.

I claim:
The ornamental design for a golf club handle, as shown.

KENNETH SMITH.
